PRESSER MECHANISM FOR SEWING MACHINES

Herman Ritter, Cranford, N. J., assignor to The Singer Manufacturing Company, Elizabeth, N. J., a corporation of New Jersey

Application November 14, 1942, Serial No. 465,533

8 Claims. (Cl. 112—235)

This invention relates to sewing machines and more particularly to presser mechanisms for sewing machines.

The usual sewing machine is provided with a lower four-motion feed-dog movable in parallel vertical planes and traversing an elliptical path which has its major axis substantially parallel to the sewing machine throat-plate. The feed-dog is positioned relative to the throat-plate so that when the feed-dog is traversing the upper portion of its path the feed-dog teeth will project above the top surface of the throat-plate. Therefore, during the first half of the feeding movements of the feed-dog, when the dog is above the top surface of the throat-plate, the feed-dog will move both upwardly and in the direction of feed, thereby to grip the work against the presser-foot and actually lift the presser-foot and presser-bar a short distance. During the latter half of the feeding movement the feed-dog moves both downwardly and in the direction of feed before dropping below the top surface of the throat-plate. The downwardly spring biased presser-foot and the presser-bar drop with the feed-dog until the down-movement of the work is arrested by the throat-plate. The work then remains stationary while the feed-dog returns below the level of the throat-plate to its initial position ready to begin another feeding stroke. These engagements of the feed-dog with the work occur once for each stitch made by the machine, and the presser-bar and foot must rise and fall with the feed-dog once for each stitch.

Due to the movement of the feed-dog in the direction of feed the work is drawn under the sole portion of the presser-foot thereby introducing a sidewise thrust into the presser-bar. This sidewise thrust sets up frictional forces between the presser-bar and its bearings and thus this frictional force coupled with the natural inertia of the usual presser-bar tends to prevent the presser-bar from returning quickly to its lower position when the feed-dog moves downwardly.

As the speed of a sewing machine is advanced it becomes increasingly difficult to return the presser-foot quickly and forcefully down upon the work at the end of the feed-advance stroke of the feed-dog. At these higher speeds of operation of the machine, the friction between the usual presser-bar and its bearings is so materially increased due to the increased speed of the work under the presser-foot sole portion, that the spring which is used to return or lower the presser-bar cannot function to completely lower the presser-foot between consecutive work-dis-

engaging and work-engaging movements of the feed-dog. In this connection it is to be understood that there are limits to the pressure which may be exerted, without detriment, by presser-bar springs and particularly with certain classes of work.

This sidewise thrust which is developed in the presser-bar when the machine is operating at high speed is increased greatly whenever the 10 presser-foot encounters a cross-seam or a slight increase in thickness of the work. Such an increase in work thickness forms an obstruction which raises the toe portion of the presser-foot thereby to introduce a relatively large backward 15 force into the presser-foot, which force increases the sidewise thrust of the presser-bar. Consequently it is difficult to stitch work of irregular thickness at high speeds on sewing machines of the type heretofore used.

20 It is an object of the present invention to provide a presser mechanism which is adapted for high speed operation and constructed so as to minimize the bearing friction therein.

It is a further object of the present invention 25 to provide a presser mechanism having a very small amount of inertia so that the presser-foot will readily follow the vertical movement of the feed-dog.

The invention both in structure and in operation, as well as additional objects thereof, will be best understood from the following description taken in conjunction with the accompanying drawing in which:

Fig. 1 is a front elevation of the head of a sewing machine embodying my invention, the face-plate being removed.

Fig. 2 is a side elevation partly in section of a portion of the present presser mechanism.

Fig. 3 is a front elevation, partly in section, of 40 a portion of the present presser mechanism.

Fig. 4 is a sectional view taken substantially along line 4—4 of Fig. 1.

In the embodiment selected for illustration 45 represents the hollow head of a sewing machine frame into which projects the forward end of the usual rotary needle-bar shaft 11. This end of the shaft 11 carries the usual take-up and needle-bar operating cranks 12 and 13, respectively. The needle-bar crank 13 is directly connected by 50 means of the link 14 to a needle-bar 15, carrying the eye-pointed needle 16 and journaled in the bearings 17 and 18 fixed in the hollow head 10.

The take-up is of the so-called link or crank operated type and comprises the usual angle-lever having rigidly related arms 19 and 20, the

former of which embraces the take-up operation crank 12, and the latter of which is formed with the thread-eye 21. The lever 19, 20 is pivotally connected at the junction of its arms to one end of the anchor-link 22, the opposite end of which is pivoted at 23 to the head 10 of the machine. It will be understood that the arm 20 of the take-up lever extends through a slot 24 in the head of the machine.

The above partially described machine is fully disclosed in the patent to Richard Kaier, No. 2,206,285, dated July 2, 1940, to which reference may be had for a more complete description of the sewing machine.

Also located within the hollow head 10 is a presser-bar 25 journaled in the bearing 26 which is fixed within the head 10 by means of a set screw 27. The presser-bar 25 is yieldingly urged downwardly by means of a compression spring 28 the top portion of which bears against the adjusting screw 29 and the bottom of which engages a block 30 fixed to the presser-bar 25. This block 30 may be adjusted along the presser-bar through the medium of the set screw 31 which secures the block in place. Loosely surrounding the presser-bar 25 is a collar 32 having a shoulder 33 to which the bottom portion of a link 34 is pivotally secured. The top portion of the link 34 is apertured at 35 and receives one end 36 of the usual treadle-operated presser-bar lifter. When this lifter 36 is raised it carries the collar 32 with it and the collar by engaging the block 30 raises the presser-bar against the action of the compression spring 28.

The presser-bar 25 may also be raised by swinging the usual hand lever 37 upwardly about its pivot 38 thereby to engage the shoulder 33 which in turn bears against and lifts the block 30.

Secured upon the lower end portion of the presser-bar 25 by means of a set screw 39 is a bracket 40 from which extends the inclined bearing tube 41. Slidably mounted within the tube 41 is a presser-foot plunger 42 to the lower end portion of which is rigidly secured the usual presser-foot 43 by means of the screw 44. The tube 41 and plunger 42 are located in a vertical plane containing the line of feed and they are inclined upwardly in the direction of feed at an angle of about 60° with the usual machine cloth-plate or work-support 45. The presser-foot is normally situated directly beneath the presser-bar 25.

The presser-bar 25 is in the form of a hollow tube which slidably receives within its lower end the spherical head 46 of a relatively short thrust-pin 47 of which the lower sharpened end pivotally engages a notched portion 48 of the plunger 42. Contained within the hollow presser-bar 25 is a vertically disposed compression spring 49 the upper end of which engages the depending rod 50 and the lower end of which engages the spherical head 46 of the thrust-pin 47, thereby to apply the required spring pressure to the presser-foot 43. This pressure may be varied by turning the adjusting screw 29 in the normal manner. The upper end of the rod 50 is fixed to the adjusting screw 29 and the lower end thereof is slidably received within the upper end of the presser-bar 25. The downward movement of the presser-bar 25 is limited by the position of the hand lever 37 against which the collar 32 bears and the spring 28 is strong enough to hold the presser-bar 25 in its lowest position during the feeding operations of the mechanism. Fig. 1 shows the presser-bar 25 in its lowest position and by ad-

justing the block 30 the lower or normal sewing position of the presser-bar may be varied.

The upper portion of the tube 41 is cut away as at 51 to afford a slideway for a block 52 which is secured to the plunger 42 by means of a screw 53. Whenever the presser-bar is raised by either the member 36 or the lever 37 the tube 41 will be raised and in so doing a shoulder 54 thereof will engage the block 52 thereby to elevate the plunger 42 and presser-foot 43 assembly against the action of the spring 49 the top portion of which is prevented from any upward movement by means of the normally stationary rod 50.

The work to be stitched is intermittently advanced across the cloth-plate 45 by a feeding mechanism of the lower four-motion type and including a feed-dog 55, carried by a feed-bar 56 and projected through suitable feed-slots in the throat-plate 57. Any suitable mechanism may be employed for imparting the usual rising and falling, and the work-advancing and return movements to the feed-dog 55.

As hereinabove described, the feed-dog 55 in its work-advancing stroke raises the presser-foot 43 and exerts a backward and an upward thrust thereupon. Thus the present presser-foot, when raised by the feed-dog, must move both upwardly and backwardly against the action of the spring 49, as guided by the tube 41, and the thrust-pin 47 will pivot about its spherical head 46 within the presser-bar to permit its sharpened end to follow the presser-foot plunger 42. The tube 41 has been tilted substantially 60° with the cloth-plate 45 as it has been found that by so doing the plunger 42 will lie substantially in the direction of the resultant feed-dog thrust. The presser-foot, therefore, in moving upwardly and backwardly moves in the direction of feed-dog thrust thereby to obviate the usual presser-bar bearing friction resulting from the excessive side pressure of the presser-bar upon its lower bearing.

Fig. 2 illustrates the presser-foot 43 as it first engages a cross-seam 58 of a work-piece 59. It may be readily seen that such a cross-seam would cause the presser-foot not only to rise vertically but it would also tend to move the foot in a backward direction. Thus in the present case the presser-foot may move both in a backward as well as in an upward direction without causing any binding in the presser-bar bearing 26. These movements of the presser-foot, due to the variations in work thickness and the rising and falling of the feed-dog, are not transmitted to the presser-bar 25 which, because of its relatively greater inertia and the frictional forces that are exerted upon it by the rod 50 and the bearing 26, tends to remain in a fixed position. The relatively light compression spring 49 is therefore able to return the presser-foot quickly to its downward position when the feed-dog 55 completes its work-advancing stroke.

Having thus set forth the nature of the invention what I claim herein is:

1. The combination in a sewing machine having a work-support, a head spaced from said work-support, and a needle-bar reciprocably journaled within said head and operable in a path substantially perpendicular to said work-support, of bearing means sustained by said head, a plunger journaled for endwise movement within said bearing means, said plunger being inclined relative to said work-support, a presser-foot secured upon the lower end of said plunger, and spring means in engagement with said plunger,

said spring means exerting a thrust upon said plunger in a direction perpendicular to said work-support.

2. In a presser-mechanism for sewing machines, a hollow presser-bar, means to hold said presser-bar stationary at a predetermined operative position, bearing means carried at the lower end of said presser-bar, a plunger slidably mounted within said bearing means and being disposed at an angle with the axis of and in a plane containing said presser-bar, a compression spring carried within said hollow presser-bar, the lower end of said spring being operatively connected with said plunger to force the latter in a downward direction, and a presser-foot carried by the lower end of said plunger.

3. In a sewing machine, a frame including a hollow head, a presser-bar endwise slidably mounted in said head and formed with a cavity extending longitudinally thereof, a bracket fixed to the lower end of said presser-bar beneath said head, a plunger slidably mounted within said bracket and inclined relative to said presser-bar, a spring disposed in the cavity in said presser-bar, means at one end of said spring to transmit the force thereof to said plunger, and a presser-foot carried by the lower end of said plunger.

4. In a sewing machine, a frame including a hollow head, a needle-bar endwise slidably mounted in said head, a bracket sustained by and disposed beneath said head, a plunger slidably carried within said bracket, said plunger being inclined relative to said needle-bar, a spring disposed within said head, means at one end of said spring to transmit the force thereof to said plunger, and a presser-foot carried by the lower end of the plunger.

5. The combination in a sewing machine having a frame including a hollow head, a work-support, and a lower four-motion feed dog, of a presser-bar endwise slidably mounted in said head and formed with a cavity extending longitudinally thereof, a bracket fixed to the lower end of said presser-bar beneath said head, a plunger slidably mounted within said bracket, said plunger being inclined relative to said work-support and being contained within a plane disposed in the direction of feed, a presser-foot carried by the lower end of said plunger, a spring carried within

the cavity of said presser-bar, means at one end of said spring to transmit the force thereof to said plunger, and means extending into said hollow head for varying the force of said spring.

5. 6. In a sewing machine, a frame including a hollow head, a hollow presser-bar endwise slidably mounted in said head, means to hold said presser-bar stationary at a predetermined operable position, a bracket fixed to the lower end of said presser-bar, a tubular bearing member extending upwardly from said bracket and being inclined relative to said presser-bar, a plunger slidably journaled within said tubular bearing member, a presser-foot mounted upon the lower end of said plunger, a spring disposed within said hollow presser-bar, and pivotal means at one end of said spring for engaging said plunger and transmitting the force of the spring thereto.

7. In a sewing machine, a frame including a hollow head, a needle-bar endwise slidably mounted in said head, a bracket sustained by and disposed beneath said head, a tubular bearing member extending from said bracket, said tubular bearing member having its longitudinal axis forming an angle of about 30° with the axis of and lying in a plane containing said needle-bar, a plunger slidably journaled within said tubular bearing member, means associated with said plunger to limit its downward movements, a presser-foot carried upon one end of said plunger, a spring sustained by said head, and means at one end of said spring to transmit the force thereof to said plunger.

8. In a presser-mechanism for sewing machines, a hollow presser-bar, means to hold said presser-bar stationary at a predetermined operative position, a bracket sustained by and disposed upon the lower portion of said presser-bar, a tubular bearing member extending upwardly from said bracket and being inclined relative to the axis of and lying in a plane containing said presser-bar, a plunger slidably journaled within said tubular bearing member, a presser-foot carried upon the lower end of said plunger, a compression spring carried within said hollow presser-bar, and a thrust-pin having one end thereof in engagement with said spring and its other end pivotally engaging said plunger.
